United States Patent Office

Des. 186,980
Patented Jan. 5, 1960

186,980

FOOD CART

Victor D. Molitor, Englewood, Colo.

Application May 6, 1957, Serial No. 46,023

Term of patent 14 years

(Cl. D14—3)

FIG. 1.

FIG. 2.

Fig. 1 is a front perspective view of a food cart embodying my new design; and

Fig. 2 is a rear perspective view of the food cart of Fig. 1.

The essential features of my design are shown in full lines.

I claim:

The ornamental design for a food cart, as shown and described.
